DUMPING BUGGY

James D. Walker, Butler, Pa.

Application September 14, 1936, Serial No. 100,719

1 Claim. (Cl. 214—64)

This invention relates to dumping buggies especially adapted for loading mine cars with ore obtained from mine rooms inaccessible to mine cars and has for the primary object the provision 5 of a device of this character which will provide saving in time and labor and may be readily set up in a mine room, whereby the buggy may be loaded and then moved to the mine car by power derived from a power source and caused to assume a dumping position to deposit the load thereof directly into the mine car.

With these and other objects in view, this invention consists in certain novel features of construction, combination and arrangement of parts 15 to be hereinafter more fully described and claimed.

For a complete understanding of my invention, reference is to be had to the following description and accompanying drawings, in which

20 Figure 1 is a side elevation showing a dumping buggy and its operating means.

Figure 2 is a top plan view illustrating the same.

Figure 3 is a perspective view showing a combined chock and cradle for the buggy.

25 Figure 4 is a fragmentary side elevation, partly in section, showing in detail the buggy assuming dumping position.

Referring in detail to the drawings, the numeral 1 indicates a mine comprising the usual main passage 2 in which travel mine cars 3 for the purpose of conveying to the surface of the ground ore taken from rooms 4 extending laterally from the main passage and inaccessible to the mine cars due to the dimensions of such room and also in 35 many instances located in a plane other than the plane of the main passage, as clearly shown in the drawings. These rooms may extend for a considerable distance from the main passage necessitating the conveying of the ore from said 40 rooms to the main passage. In order to easily, quickly and cheaply transfer this ore, a dumping buggy 5 is provided and made to operate on a track 6 and a combined chock and cradle 7 is located at the mouth of the room so that when 45 the buggy arrives at a point adjacent the main passage it will assume a dumping position and deposit its load directly into the mine car 3.

The buggy 5 includes a body 8 supported by car wheels 9 adapted to travel on the track 6. One 50 end of the body is closed by a removable tail gate 10 secured to and movable with arms 11 pivoted to the body 8 adjacent the other end thereof. Normally the arms 11 parallel the sides of the body positioning the tail gate to close the open 55 end of the body. Projections 12 are secured to

the body 8 and extend beyond the tail gate to engage with the chock when the buggy is moved into the combined chock and cradle.

The combined chock and cradle consists of a bed 13 on which the track 6 terminates and secured to the bed are members 14 terminating at one end of the bed in upwardly and rearwardly inclined chock elements 15 to be engaged by the projections 12 of the buggy. Side panels 16 rise upwardly from the bed 13 and may be reinforced by a cross brace 17 and by uprights 18 to engage with the ceiling of the room 4. At the entrance end of the combined chock and cradle, the panels 16 are provided with diverging wings 19. The side panels 16 act as guides for the buggy during 15 its movements from dumping to non-dumping position.

In mines it is frequently necessary to ventilate the rooms 4 and a power source 20 is provided for driving a fan 21 acting to circulate air into the 20 rooms 4. The power source 20 may be employed for furnishing power for the operation of the buggy 5 and also for the movement of mine cars in the main passage relative to the rooms 4.

Drums 22 and 23 are suitably journaled in the 25 mine opposite the room 4 and located adjacent the drum 22 is a drum 23'. Gearing 24 connects the power source with the drum 23 or to a shaft 25 acting as a support for the drums 22 and 23, the latter being connected and disconnected to said 30 shaft by clutches 26. The shaft 25 is also geared to a shaft 27 on which the drum 23' is journaled. A clutch 28 connects and disconnects the drum 23 with the shaft 27. Brake mechanisms 29 are provided for the drums heretofore mentioned. 35

Secured to and wound on the drums 22 and 23 are cables 30 and 31. The cable 31 is secured to the tail gate 10 by a hook 32 fitting in an eye 33. The cable 30 is secured to the opposite end of the body of the buggy to the tail gate in a similar 40 manner after passing over a pulley 34 secured to a wall of the room 4 and passing beneath the buggy. The drum 22 and the cable 30 are employed for drawing the buggy into the room 4 and the drum 23 and cable 31 are employed for drawing the buggy into the combined chock and cradle 45 7 and also for causing the buggy to assume dumping position, as shown in dotted lines in Figure 1. When the projections 12 engage the chocks 15 and on further winding of the cable 31 on the 50 drum 23 the buggy is caused to assume dumping position and the tail gate moved free of the discharge end of the buggy whereby the load of the buggy may gravitate into the mine car.

A cable 35 is secured to and wound on the 55

drum 23' and its free end is provided with a hook 36 which may be engaged with an end of the mine car so that on winding the cable 35 on the drum 23' the mine car will be caused to move in the 5 main passage and relative to the room 4.

Having described the invention, I claim:

In a mining apparatus, a portable frame adapted to be secured in a fixed position within a mine room entrance adjacent a loading passage and 10 having spaced longitudinally extending members fashioned with angularly disposed end sections extending upwardly and inwardly towards the center of said frame and constituting chocks located at the ends of said members positioned adjacent said passage, track members secured within said frame in parallelism with said first mentioned members and extending into a mine room, a buggy normally mounted on said track members and wheelable over the latter into and out of said 15 frame, said buggy fashioned with a closed end and

a discharge end having chock engaging projections extending therefrom, spaced arms embracing said buggy and having ends pivoted to said buggy adjacent the closed end thereof, a gate secured to said arms at the opposite ends for closing the discharge end of said buggy when the latter is in wheelable engagement with said track members, and power means connected to said gate and passing through said frame for wheeling said buggy into said frame in a manner whereby continued movement of said buggy by said power means toward said chocks effects engagement of said projections with said chocks and pivots said buggy upwardly out of engagement with said track members and pivots said arms relative to 10 said buggy to simultaneously move said gate to open position to allow the contents of said buggy to discharge through said discharge end of said buggy above said loading passage.

JAMES D. WALKER. 20
